UNITED STATES PATENT OFFICE.

FRANK F. SAVAGE, OF CHICAGO, ILLINOIS.

DESIGN FOR A SEWING-MACHINE TABLE-TOP.

SPECIFICATION forming part of Design No. 35,526, dated December 31, 1901.

Application filed January 31, 1901. Serial No. 45,522. Term of patent 14 years.

To all whom it may concern:

Be it known that I, FRANK F. SAVAGE, a citizen of the United States, residing at Chicago, in the county of Cook and State of Illinois, have invented and produced a new and original Design for Sewing-Machine Table-Tops; and I do declare the following to be a full, clear, and exact description of the same, reference being had to the accompanying drawings, forming a part of this specification.

This invention relates to a design for a table-top for sewing-machine stands or tables; and my said design consists in the structural configuration hereinafter described, and illustrated in the accompanying drawings, which form a part of this specification.

In the accompanying drawings, Figure 1 is a plan view, and Fig. 2 a transverse section at line xx , Fig. 1.

Referring to the drawings, the present sewing-machine table-top has a rectangular form and comprises in the present invention a main

border or body portion 1 and an L-shaped insert or portion 4, let into said body portion, with its upper surface flush with the top of the body portion.

2 is a main central opening or orifice in the table-top, which in the present invention has its margins formed in part by the body portion 1 and by the L-shaped insert 4, as illustrated in Fig. 1 of the drawings.

3 represents minor orifices or openings in the table-top formed near one end of the main opening or orifice 2.

I claim—

The design for a sewing-machine table-top, substantially as herein shown and described.

In testimony whereof witness my hand this 25th day of January, 1901.

FRANK F. SAVAGE.

In presence of—

ROBERT BURNS,
HENRY A. NOTT.
